UNITED STATES PATENT OFFICE.

ELBERT CECIL WILLIAMS, OF DAYTON, OHIO.

SAFETY BELT STRAP.

Application filed June 27, 1923. Serial No. 648,170.

To all whom it may concern:

Be it known that I, ELBERT CECIL WILLIAMS, a citizen of the United States, residing at Dayton, in the county of Montgomery and State of Ohio, have invented certain new and useful Improvements in Safety Belt Straps, of which the following is a specification.

This invention relates to apparel and more particularly to an attachment for retaining belts in the proper position on garments.

The object of this invention is to provide a simple and inexpensive retaining means for a belt to be used in combination with the ordinary belt guide on a garment whereby the movement of the belt in the guide will be limited.

It is well known that belts, especially those on overcoats, are very easily twisted unknown to the wearer and also when wearing a coat open and the belt unfastened, the belt usually slides through the belt guides and hangs loosely or drags and in many instances is entirely removed from the garment. This invention is designed to prevent both the twisting of the belt and the sliding of the same so that the belt cannot be lost by disconnection of the same thereof with the garment unknown to the wearer.

In the drawings, wherein like parts are designated by like characters in the several views,

Fig. 1 is a perspective view of the attachment applied.

Fig. 2 is an enlarged view of the attachment as shown in Fig. 1, and

Fig. 3 is a section taken on line 3—3 on Fig. 2.

Referring to the parts by reference numerals, a garment is designated by the numeral 10 having the ordinary belt guides 11 and a belt 12. The belt retaining attach-

ment is a strip 13 preferably of the same material as the belt, the same having one end stitched or otherwise permanently fastened to the belt at 14 and having a detachable fastener 15 at the opposite end. It is obvious that the belt 12 must be provided with means to co-act with the fastener 15. The retaining strip 13 is so positioned on the belt as to be arranged adjacent one of the guides 11 so as to embrace the guide as shown in Fig. 1 and when the fastening member 15 is secured to the belt, movement of the belt relative to the guide is limited. If so desired the detachable feature of the invention can be dispensed with and the strip 13 can be permanently fastened to the belt at both ends. As many of these strips can be used as seen fit, that is, the belt may be provided with a retaining strip for each belt guide or only one or two strips used, however, in the latter instance it is preferable to use the same with the belt guides nearest the front of the garment.

With this attachment the belt is not only prevented from becoming accidentally detached from the garment or being twisted unbeknown to the wearer, but also the ends of the belt are always in the proper accessible position for the wearer to fasten or buckle the belt as the case may be.

What is claimed is:

The combination of a garment having a belt loop thereon, a belt passing through the loop, a strip secured to the belt at one side of the loop and extending over the loop, and detachable securing means, carried partly by the free end of the strip and partly by the belt, for detachably securing the free end of the strip to the belt at the other side of the belt loop.

In testimony whereof I affix my signature.

ELBERT CECIL WILLIAMS.
